DRAFT AND BUFFER GEAR

**Stacy B. Haseltine, Chicago, Ill., assignor to
W. H. Miner, Inc., Chicago, Ill., a corporation
of Delaware**

Application November 8, 1933, Serial No. 697,163

7 Claims. (Cl. 213—9)

This invention relates to improvements in draft and buffer gears especially adapted for mine cars.

One object of the invention is to provide a combined draft and buffer gear for mine cars wherein both the draft and buffering forces are cushioned by the same shock absorbing means, which is directly actuated by the buffering heads, and wherein simple and efficient mechanism is provided for transmitting the draft or pulling forces from the car coupling means to the buffering heads.

A more specific object of the invention is to provide in a mechanism of the character set forth in the preceding paragraph a pair of shock absorbing members cooperating with each buffering head and simple and efficient lever means arranged to transmit the draft force directly to the buffering heads in such a manner that the pressure is equalized between the shock absorbing mechanisms of each pair.

Other objects of the invention will more clearly appear from the description and claims hereinafter following.

In the drawing forming a part of this specification, Figure 1 is a horizontal sectional view, partly broken away, of one end portion of a mine car illustrating my improvements in connection therewith, the section being in three different planes and corresponding substantially to the line 1—1 of Figure 2. Figure 2 is a part front elevational view and part vertical sectional view of construction shown in Figure 1, the section being on the line 2—2 of Figure 1; and Figures 3 and 4 are vertical sectional views corresponding respectively to the lines 3—3 and 4—4 of Figure 2.

In said drawing, 10 designates the end portion of a mine car to which my improved combined draft and buffer gear is attached. My improvement comprises broadly a support A; a pair of buffering caps B—B; four shock absorbing springs C—C and C—C; a pair of levers D—D; and a coupling connection E.

The support A is in the form of a housing, having spring chambers 11—11 at opposite sides thereof. The support A may be formed integral with the end portion 10 of the car, that is, the support may be a part of the end sill structure of the car. Each chamber 11 of the support A is defined by spaced top and bottom walls 12 and 13, and a vertical end wall 14. The top and bottom walls 12 and 13 are offset inwardly at the outer sides of the chambers 11 as clearly shown in Figure 2, said offset portions being in-

dicated by 15—15. As will be evident upon reference to Figure 2, the spring chambers 11 are thus formed with contracted sections at the outer sides thereof. At the inner side each chamber 11 is provided with a relatively shallow, vertical web 16 forming the inner wall of said chamber. At the top and bottom ends the wall 16 is provided with relatively short, horizontally disposed, laterally extending wall sections 17—17, which as hereinafter more fully described, provide means for supporting one of the coils of the corresponding pair of shock absorbing springs C—C. The top and bottom walls 12 and 13 of each spring chamber 11 are provided with aligned pivot pin-receiving openings 18—18 at their inner ends, as clearly shown in Figures 1, 2, and 4. The pivot pin openings 18—18 are suitably reinforced by bosses 19—19.

The buffering caps B—B are of similar design, each cap having a vertical front wall 20 provided with a transversely curved outer buffering face as shown on Figure 1. Each cap B also has spaced parallel vertical side walls 21—21 and horizontally disposed top and bottom walls 22—22. Each buffering cap B is also provided with inwardly extending guide grooves or slots 23—23 in the top and bottom walls thereof. The guide grooves 23—23 are closed at their inner ends by curved walls 24—24, which form bearing seats for pivot means on the outer ends of the levers D—D as hereinafter more fully described. Each buffering cap B is telescoped within the chamber 11 at the corresponding side of the gear.

The shock absorbing springs C—C and C—C are arranged in pairs at opposite sides of the mechanism. The springs C—C of each pair are spaced laterally as clearly shown in Figures 1 and 2, and have their rear ends bearing respectively on the inner side of the front wall 20 of the corresponding cap B and the vertical rear wall of the support A.

The levers D—D serve to transmit draft or pulling forces to the buffering caps B—B. Each lever D is pivoted between its ends on the support A by means of a pin 25, extending through the lever and through the openings 18—18 of the top and bottom walls 12 and 13 of the corresponding spring chamber 11. At the outer end each lever D is forked as indicated at 26. The forked portion 26 embraces the corresponding spring cap B, and has inwardly projecting trunnions 27—27 thereon, which engage within the top and bottom grooves 23—23 of said cap. The inner ends of the levers D—D are hinged to each other by means of a pin 28 extending through 105

110

spaced hinge eyes 29—29 and 29—29 of the levers D.

The levers D—D may be connected to the coupling means of an adjacent car in any suitable manner, but as herein shown a coupling connection E in the form of a U-shaped member is preferably provided. The top and bottom arms of the U-shaped coupling connection E straddle the hinge eye portions of the levers D—D, and the 10 pin 28 which connects the inner ends of the levers also serves to pivotally connect the member E to said levers. As will be evident, the coupling connection E may have the usual chain connection or other coupling means attached thereto.

15 The operation of my improved draft and buffer gear is as follows: the buffing heads B—B will be moved inwardly upon contact with the buffing mechanism of an adjacent car, thereby compressing the shock absorbing springs C—C and C—C

20 directly against the end of the car. Upon a pulling or draft force being applied to the coupling connection E, the inner ends of the levers D—D will be swung outwardly, thereby swinging the outer ends of the levers inwardly toward the car 25 and forcing the buffing caps B—B against the springs C—C and C—C. As will be evident, the shock absorbing springs C—C and C—C are thus compressed in the same direction in both buff and draft. Outward movement of the caps B—

30 B is limited by engagement of the trunnions 27—27 and 27—27, of the levers D—D, with the bearing seats 24—24 and 24—24 at the inner ends of the slots 23—23 and 23—23. Inasmuch as the inner ends of the levers D—D bear on the vertical 35 wall of the support A when the parts are in the normal position, movement of the levers will be limited, thereby restricting the outward movement of the buffing caps B—B.

As will be evident to those skilled in this art, 40 my improved arrangement of levers which transmit the draft forces to the buffer caps assures full compression of the shock absorbing springs in draft together with equalization of the load on the members of each pair of springs, thereby 45 giving maximum efficiency at all times during operation of the gear.

I have herein shown and described what I now 50 consider the preferred manner of carrying out my invention, but the same is merely illustrative and I contemplate all changes and modifications 55 that come within the scope of the claims appended hereto.

I claim:

1. In a combined draft and buffer gear for 55 cars, the combination with a fixed abutment means on the end of the car; of cushioning means bearing on and compressible against said abutment means; a pair of laterally spaced buffing caps, slidably mounted on the end of the car, and movable inwardly towards the end of the car in buff to compress the cushion means against the abutment means; an outwardly movable coupling member at the end of the car, said coupling member being disposed between the buffing heads; 60 and a pair of levers for transmitting the draft force from the coupling member to the buffing caps, said levers being swiveled to the buffing caps and pivoted between their ends on said abutment means.

70 2. In a combined draft and buffer gear for cars, the combination with a fixed support on the end of the car; of a pair of buffing caps at opposite sides of the end of the car; shock absorbing members adapted to receiving buffing shocks 75 from said caps and be compressed against the end

of the car; and levers pivoted between their ends on said support, said levers being connected at their inner ends to a coupling member and having their outer ends swiveled to the buffing caps.

3. In a combined draft and buffer gear for 80 cars, the combination with a pair of laterally spaced buffer caps at the end of the car, said caps being movable inwardly of the car when a buffering force is applied thereto; of a pair of levers between said buffer caps, said levers being pivotally connected to each other at their inner ends, said connected ends being movable outwardly away from the end of the car when a pulling force is applied thereto; means on the car for pivotally supporting the levers between their ends; means 85 for pivotally connecting the outer ends of said levers to said buffer caps respectively; and cushioning means opposing inward movement of each buffer cap.

4. In a combined draft and buffer gear for cars, 90 the combination with a fixed abutment means on the end of the car; of a supporting member; a pulling member; buffing caps at opposite sides of the pulling member, said caps being slidably inwardly on the supporting member; a pair of 100 laterally spaced cushioning members interposed between each cap and the abutment means and opposing inward movement of said cap; and levers pivotally connected at their inner ends and pivotally supported between their ends on said 105 supporting member at opposite sides of the pulling member, the outer end of each of said levers being connected to the corresponding buffing cap at a point between the corresponding pair of cushioning members.

5. In a combined draft and buffer gear for cars, 110 the combination with fixed abutment means on the end of the car; of a supporting member; a buffer cap movable inwardly on the supporting member, said cap having inwardly extending 115 guide grooves on opposite sides thereof, said grooves being closed at their inner ends; cushioning means interposed between said cap and abutment means; a pulling member movable outwardly away from the end of the car in draft; and a 120 lever pivoted between its ends on said support, said lever having one end connected to the pulling member and having aligned, oppositely disposed trunnions at the other end, said trunnions 125 engaging within the grooves of the buffer cap.

6. In a combined draft and buffer gear for cars, 130 the combination with fixed abutment means on the end of the car; of a supporting member; a pair of laterally separated buffer caps movable inwardly on the supporting member; cushioning means bearing on said abutment means and opposing inward movement of said buffer caps; a pulling member movable outwardly away from the car in draft; a pair of levers swiveled to the 135 buffer caps and extending laterally inwardly toward each other, each lever being fulcrumed between its ends on the supporting member; and a pivot pin connecting the inner ends of the levers and also connecting said levers to the pulling member.

7. In a combined draft and buffer gear for cars, 140 the combination with a fixed support at the end of the car, said support having spring chambers at opposite sides thereof; of buffer caps slidably telescoped within said spring chambers, each cap having top and bottom inwardly extending guide grooves closed at their inner ends; a pair of laterally spaced shock absorbing springs in each spring chamber bearing on the corresponding buffer 145 150

cap; a pair of levers extending inwardly toward each other, said levers being pivotally mounted between their ends on said support and hinged to each other at their inner ends, each lever being forked at the outer end, the forked portion of said lever embracing the corresponding buffer cap and having trunnions thereon engaging in the top and bottom grooves of said cap, said trunnions bearing on the closed inner ends of said grooves during the draft action of the gear; and a pulling member connected to the hinged portion of said levers. 80
